By Robert S. Carr, Atty.

UNITED STATES PATENT OFFICE.

WILLIAM H. SHAFER, OF CINCINNATI, OHIO, ASSIGNOR TO THE AHRENS FIRE ENGINE COMPANY, OF CINCINNATI, OHIO, A CORPORATION OF OHIO.

STEAM-GENERATOR.

No. 799,196.

Specification of Letters Patent.

Patented Sept. 12, 1905.

Application filed February 10, 1905. Serial No. 245,147.

To all whom it may concern:

Be it known that I, WILLIAM H. SHAFER, a citizen of the United States, residing at Cincinnati, Ohio, have invented a new and useful Improvement in Steam-Generators, of which the following is a specification.

My invention relates to steam-generators of the combined fire and water tube class adapted for the use of fire-engines and for other purposes; and the objects of my improvement are to provide a series of independently-detachable units of generation each having interior and exterior channels forming cycles of circulation, the latter channels being helical in form to secure the maximum heating-surface and to maintain the direction of circulation; to superheat the steam by contact with the flues in its discharge from the generating units; to permit the discharge of water from the units only in the form of steam, and in the construction and assemblage of parts to maintain simplicity with maximum efficiency and to facilitate the removal of parts for repairs. These objects are attained in the following-described manner, as illustrated in the accompanying drawings, in which—

Figure 1 is a vertical diametrical section of a steam-generator embodying my improvement; Fig. 2, an elevation with parts in section of portions of a generating unit, showing its connection with the crown-sheet and water-leg of the generator; Fig. 3, a plan of the crown-sheet, and Fig. 4 an inverted plan of the lower header of a generating unit.

In the drawings, 5 represents the outside shell of a vertical cylindrical generator or boiler, 6 the head, 7 the inside shell, 8 the crown-sheet, 9 the water-leg, 11 the fire-box, 12 the steam-chamber, 13 a horizontal partition therein, 14 the steam-supply pipe, 15 the flues or fire-tubes secured in the head and crown-sheet and passing loosely through openings in the partition, and 16 the smoke-hood, all constructed and arranged in the ordinary manner.

A series of generating units 17, depending within the fire-box from the crown-sheet, communicate with the water-leg through respective supply-pipes 18 and with the steam-chamber through respective nozzles 19, which are formed with lateral discharge-openings 21 above the water-line 22. Said units each consists of hollow top and bottom headers 23 and 24, connected together by axial tube 25, and

a series of parallel tubular helices 26, which 55 encircle the axial tube without contact therewith or with each other. The headers are each formed with channels 27, which radiate from a central chamber 28 to the respective helices, and with openings 29, provided with 60 removable plugs 30 in registration with said helices to permit access for swaging or cleaning purposes.

The top headers are each formed with a recess 31, encircled by collar 32, wherein the 65 axial tube terminates, and with threaded sleeve 33, wherein the nozzle is secured and which is removably secured within an opening 34, formed in the crown-sheet. The lower end of said sleeve terminates within the central chamber near recess 31. The bottom headers are each removably secured to a corresponding supply-pipe 18 by means of an angular fitting 35, which is formed with opening 36, provided with removable plug 37 in 70 registration with the axial tube. Pipes 38, attached to plugs 37, are extended through the corresponding axial tubes concentric therewith and encircled by the respective annular channel 39. Said pipes are each formed 75 with lateral discharge-openings 41 in its lower portion, and they terminate in flanged mouths 42 within the respective recesses 31.

In operation the greater length and position of exposure of the helices to the fire cause 85 them to generate steam more rapidly than do the axial tubes, whereby primary cycles of generation therethrough from the water-leg to the steam-chamber are automatically maintained. The pipes within the axial tubes being protected thereby from direct contact with the fire form descending passages for the water from the top to the bottom headers, whence it ascends again through the annular channels, whereby secondary cycles of generation 90 are automatically maintained. The steam from the series of units is discharged by the nozzles in contact with the fire-tubes within the steam-chamber, whence it passes 95 through openings in the partition to the supply-pipe.

The units are separately removable to facilitate repairs or substitution by others.

Having fully described my improvement, what I claim as my invention, and desire to 105 secure by Letters Patent of the United States, is—

1. In a steam-generator, a top header ar-

- ranged to detachably engage with the crown-sheet and provided with a vertical nozzle having lateral discharge-openings, a bottom header, and a helical tube extending between 5 the headers.
2. In a steam-generator, the combination of a top header arranged to detachably engage with the crown-sheet, a bottom header provided with a supply-pipe, and a series of tubular helices forming channels of communication between the headers said helices being concentric with a common axis and parallel with each other.
3. In a steam-generator, a unit of generation 15 consisting of a top header provided with a discharge-nozzle and arranged to detachably engage with the crown-sheet a bottom header, and an axial and a helical tube connecting them together for the purpose specified.
- 20 4. A steam-generator having in combination a top header arranged to detachably engage with the crown-sheet and provided with a vertical nozzle having lateral discharge-openings, a bottom header, and a series of tubular helices forming channels of communication 25 between the headers.
5. In a steam-generator, a unit of generation 30 consisting of a top header provided with a vertical nozzle having lateral discharge-openings, a bottom header provided with a supply-pipe, an axial tube forming a descending channel, and a series of tubular helices concentric therewith forming ascending channels, of communication between the headers.
- 35 6. In a steam-generator, a series of independent units of generation each arranged to detachably depend from the crown-sheet and within the fire-box and consisting of a top header provided with a vertical discharge-nozzle, a bottom header provided with a supply- 40
- pipe, and communicating therewith through a straight axial tube and through a series of helical tubes concentric therewith and equidistant from each other.
7. In a steam-generator, a unit of generation 45 consisting of top and bottom headers communicating through an axial tube, a pipe extending therethrough and a tubular helix.
8. In a steam-generator, a detachable unit of circulation consisting of a top header, a discharge-nozzle extending therefrom, a bottom header, a supply-pipe leading thereto, said headers being in communication through an axial tube, a pipe therein, and a series of parallel tubular helices which encircle the axial 50 tube without contact therewith or with each other.
9. In a steam-generator, a series of independent generating units arranged to detachably engage with and depend from the crown-sheet, and each consisting of a top and a bottom header respectively provided with a vertical discharge-nozzle and with a supply-pipe and communicating through concentric straight tubes registering with the nozzle and through 55 parallel helical tubes concentric with the straight tubes.
10. In a steam-generator, concentric vertical tubes communicating with top and bottom headers and a vertical discharge-nozzle in registration therewith.
11. In a steam-generator, a unit of generation 60 consisting of top and bottom headers communicating through an axial tube, a pipe therein and tubular helices encircling said axial tube.

WILLIAM H. SHAFER.
